UNITED STATES PATENT OFFICE.

IRA EVERETT, OF SAYRE, PENNSYLVANIA, AND GEORGE T. COOKE, OF NEW YORK, N. Y.

RAILWAY CAR.

Application filed September 19, 1921. Serial No. 501,591.

To all whom it may concern:

Be it known that we, IRA EVERETT and GEORGE T. COOKE, citizens of the United States, residing, respectively, at Sayre, in the county of Bradford and State of Pennsylvania, and at New York, in the county of New York and State of New York, have invented a new and useful Improvement in Railway Cars, of which the following is a specification.

This invention relates to improvements in railway cars of the type used for transporting coal, coke, ore or similar granulated substances which cars are usually constructed of metal having sloping bottoms with an opening for the discharge of cargo and are generally known as hopper cars. This invention relates more particularly to the construction of a metal door to close the discharge opening of a hopper car.

It is an object of this invention to provide a strong, light weight metal door for hopper cars which, should the door be prevented from closing tightly, will prevent the lading from sifting out during transportation, and another object is to provide a door of this character which will not necessitate the cutting away of any of its parts for the application of the usual strengthening bar that joins the adjacent doors.

Hopper cars are a recognized type in which one general form comprises bottoms which slope downward from each end toward other portions sloping downward theretowards from the center of the car, the center sills passing through the lower edges of the end slope sheets and body of the central slope sheets with the hopper doors arranged in pairs on opposite sides of the center sills adapted to close the discharge opening between the end slope sheets and central slope sheets and it is, therefore, not considered necessary to illustrate and describe in more detail this general type of car.

While the preferred form of this invention is illustrated upon the accompanying drawing, yet it is to be understood that minor detail changes may be made without departing from the scope thereof.

Fig. 1 illustrates this improved hopper door in vertical section through the central portion thereof.

Fig. 2 is a view in perspective of this improved door detached from the car body.

The embodiment of this invention as illustrated includes a hopper door attached by hinge butts to the under side and above the bottom edge of an end slope sheet between the center and side sills. The body 1 of the door is shaped to correspond with the discharge opening and extends slightly above and on the under side of the lower edge of the end slope sheet 2 and below and beyond the lower edge of the central slope sheet 3. The body of the door may be provided with parallel longitudinal corrugations 4, if desired, which are preferably pressed upward from the outer side of the door and extend in the general direction of the discharge of the load. The door is secured to the hinge butts 5 by hinge straps 6 secured to the under side of the door body as shown. The bottom and sides of the door body are provided with a continuous upwardly extending flange 7 so as to receive the side walls and central slope sheet of the hopper when the door is closed, as shown in Fig. 1.

That part of flange 7 which is integral with the lower edge of the door is bent to form an obtuse angle with the body 1 of the door so that when the door is open this flange is positioned so that the lading will not be retained thereon but will slide off. This eliminates the necessity of the cars being cleaned after each trip. It also permits a full head rivet to be used to secure the bottom stiffener angle to the central slope sheet 3.

The door is adapted, under normal conditions, to make a tight closure with the bottom edges of the wall of the hopper but often during travel from different causes the tight closure becomes imperfect and the jolting of the load during the movement of the car will cause the lading to leak or sift through between the door and walls of the hopper. The upstanding flange on the sides and bottom edges of the hopper door embracing the hopper walls will insure the retention of the lading when the closure between the door and hopper walls is imperfect.

It is customary to rigidify metal hopper doors by down turned flanges along the bottom and side edges and also to connect the pair of doors operating together on the same side of the transverse center of the car by a rigidifying brace, as illustrated, usually in the form of channel irons 8 secured to the

door bodies which necessitate another operation in the manufacture of the door as the down turned flanges on the adjacent sides of the doors must be cut away in order that 5 the connecting brace may be secured to the door body.

The hopper door constructed in accordance with this invention simplifies the manufacture, allows for the ready attachment of 10 the connecting brace and prevents the loss of the lading if the doors are imperfectly closed.

What we claim is:

1. In a railway car having hopper walls, 15 a metallic door provided with a continuous flange about the side and bottom edges thereof extending upwardly from the door body so as to embrace the lower edges of said hopper walls, said flanges deflected from the 20 door body to such an extent that the upper part of said flange is further away from said hopper wall than the lower part of said flange.
2. In a railway car having hopper walls, 25 a metallic door provided with a continuous flange about the side and bottom edges thereof extending upwardly from the door body

so as to embrace the lower edges of said hopper walls, the flange on the bottom edge deflected from the door body to such an extent that the upper part of said flange is further away from said hopper wall than the lower part of said flange. 30

3. In a railway car having hopper walls, 35 a metallic door provided with a continuous flange about the side and bottom edges thereof extending upwardly from the door body so as to embrace the lower edges of said hopper walls, the angular relation of said flange to the body of the door being different than the angular relation of the said hopper walls to the body of the door. 40

4. In a railway car having hopper walls, 45 a metallic door provided with a continuous flange about the side and bottom edges thereof extending upwardly from the door body so as to embrace the lower edges of said hopper walls, the angular relation of said flange to the body of the door being greater than the angular relation of the said hopper 50 walls to the body of the door.

IRA EVERETT.
GEO. T. COOKE.
